(57) **CLAIM**

The ornamental design for a slice and sharpen for cutting board, as shown and described.

DESCRIPTION

FIG. 1 is a top perspective view of the slice and sharpen for cutting board showing my new design.

FIG. 2 is a top view thereof.

FIG. 3 is a side view thereof.

FIG. 4 is another side view thereof.

FIG. 5 is a bottom view thereof.

FIG. 6 is another side view thereof; and,

FIG. 7 is another side view thereof.

The broken lines showing other parts of the slice and sharpen for cutting board form no part of the claimed design.
